LEG-REST AND CONTROL ARRANGEMENT FOR CHAIR

Fridtjof F. Schliephacke, Berlin-Schmargendorf, Germany, assignor to Anton Lorenz, Boynton Beach, Fla.

Filed Mar. 22, 1957, Ser. No. 647,795

5 Claims. (Cl. 155—106)

The present invention relates to articles of furniture, and in particular to an improved leg-rest and control arrangement for the type of a chair including a support and body supporting means having a seat and a back-rest rockably mounted on the support.

It is known to construct a chair including a seat and back-rest rockably mounted on a support and a leg-rest disposed adjacent the forward end of the seat with provision for coordinating movement of the seat and leg-rest to movement of the back-rest. Accordingly, when a person, seated in the chair, leans back to displace the back-rest from its normal position to a reclining position, both the seat and the leg-rest are moved to appropriate inclined and extended positions respectively to comfortably accommodate the person in a reclined or partially reclined position.

Broadly, it is an object of the present invention to provide an improved leg-rest and control arrangement for a chair of the aforesaid general construction. Specifically, it is within the contemplation of the present invention to provide an improved linkage control coordinated to movement of the back-rest of the chair which is effective to move the leg-rest upwardly and outwardly in relation to the seat of the chair in response to the reclining movement of the back-rest.

In accordance with an illustrative embodiment demonstrating features of the present invention, the improved leg-rest and control arrangement comprises a leg-rest disposed adjacent the forward end of the seat of the chair, a pivotally mounted arm, a first controlling link crossing the pivotally mounted arm and having both a pivotal and slidable connection to said arm, and a second pivotally mounted controlling link, said second controlling link pivotally mounting said arm and having a pivotal connection to said first controlling link at a location spaced rearwardly of the pivotal and slidable connection. The spacing between the pivotal mount for the second controlling link and its pivotal connection to the first controlling link is greater than the spacing between the pivotal mount for the arm on said second controlling link and its pivotal and slidable connection to the first controlling link whereby the second controlling link describes a greater arc than the first arm which in turn is effective to turn the leg-rest both upwardly and outwardly in relation to the forward end of the seat. Coordination of the improved foot-rest linkage to the back-rest and the seat is achieved by a further linkage means of known construction.

The above brief description as well as further objects and advantages of the invention will best be appreciated by reference to the following detailed description of a number of preferred embodiments, when taken in conjunction with the accompanying drawings wherein:

Fig. 1 is a side elevational view of a first embodiment of reclining chair demonstrating features of the present invention, with a portion of one side wall broken away to disclose the details of the operating mechanism at the one side of the chair;

2

Fig. 2 is a side elevational view, with portions broken away, illustrating the chair in Fig. 1 and showing the coordinated position of the seat and leg-rest when the back-rest is in the reclining position;

5 Fig. 3 is a diagrammatic showing of the linkages employed at each side of the chair in Fig. 1 for coordinating the movement of the seat and the leg-rest to the back-rest;

Fig. 4 is a side elevational view, with parts broken away, illustrating a further embodiment of reclining chair

10 demonstrating features of the present invention; and

Fig. 5 is a side elevational view of the chair illustrated in Fig. 4, but showing the coordinated position of the seat and leg-rest when the back-rest is in the reclined position.

Referring now specifically to Figs. 1 to 3 inclusive, there is shown a first embodiment of the invention which, except for the improved leg-rest arrangement, is subject to a latitude of variations and change. Specifically, it will be seen that in Fig. 1 the chair 10 has a frame 12, body-supporting means 14 having a seat 16 and a back-rest 18, and a leg-rest 20 disposed adjacent and beneath the forward end of the seat 16 and mounted for coordinated movement with the back-rest 18. In this illustrative form of invention, identical linkage arrangements are employed at each side of the chair for coordinating movement of the seat 16 and the leg-rest 20 to the back-rest. Accordingly, it will suffice to describe the details of the linkage mechanism at the adjacent side of the chair, which adjacent side has been exposed by removal of portions of the support or frame 12.

20 30 The back-rest 18 of the body-supporting means 14 is rockably mounted on the support 12 at the pivot 38. The seat 16 is mounted on the same pivot by means of a pair of rearwardly projecting bars 40 which are fixed to the seat 16 and pivotally mount the seat 16 on the support 12 at the pivot 38. The illustrative rockable mount for the seat 16 and the back-rest 18 on the support is coaxial, but the respective pivotal connection for the seat and the back-rest on the support could be spaced from each other.

An appropriate linkage arrangement is interconnected

40 45 50 55 60 between the reclining back-rest 18 and the seat 16 to transmit the movement of the back-rest 18 to the seat 16, whereby in response to reclining movement of the back-rest, the seat is displaced to the inclined position illustrated in Fig. 2. This linkage arrangement includes a guiding link 44 and first and second connecting links 48, 50. The guiding link 44 has a pivotal connection 60 at its upper end to the support 12. Intermediate its ends, the guiding link 44 has a pivotal connection 79 to one end of the connecting link 48, the other end of said connecting link having a pivotal connection 58 to the lower end of the back-rest 18 at a point spaced below the pivot 38 of the body-supporting means 14 on the support 12. The seat connecting link 50 has its upper end pivotally connected to the seat 16 at the pivot 64 and has its lower end pivotally connected to a lateral extension of the guiding link 44 at the pivot 66. The extension is integral with the guiding link 44 at a point spaced above the pivotal connection 79. The described linkage arrangement is effective to transmit the reclining movement of the back-rest 18 into coordinated rocking movement of the seat 16 about the pivot 38. This coordinated movement may be appreciated by progressively inspecting the relative positions of the seat and back-rest in Figs. 1 and 2.

In accordance with the present invention, the improved leg-rest control arrangement embodies an arm 70 disposed adjacent to the forward end of the seat and having its upper end pivotally mounted as will be described hereinafter.

Extending across the arm 70 is a first controlling link 76 which is connected at its rearward end to the guiding link 44 and at its forward end to the leg-rest 20. At a location intermediate its ends, the first controlling link

76 has a pivotal and slidable connection to the arm 70. The pivotal connection at the rearward end of the first controlling link to the guiding link 44 has been designated by the reference numeral 62; the pivotal connection at the forward end of the first controlling link to the leg-rest 20 has been designated by the reference numeral 86; and the pivotal and slidable connection between the first controlling link 76 and the arm 70 includes the pin 80 on the link 76 and the elongated slot 82 formed in the arm 70.

Intermediate the lower end of the arm 70 and the leg-rest 20 is a further connecting link 92 which has a pivotal connection 94 at its forward end to the leg-rest 20 at a location spaced below the pivotal connection 86 and a pivotal connection 90 at its rearward end to the lower end of the arm 70.

As may be appreciated by progressively inspecting Figs. 1 and 2, the pin 80 of the pin and slot connection moves between the upper end of the slot 82 (Fig. 1) and the lower end of the slot 82 (Fig. 2) when the leg-rest 20 is extended in relation to the seat 16 in response to reclining movement of the back-rest 18. In order to effectively guide the pin 80 in its limited travel in the slot 82, a second controlling link 96 is operatively connected to the first controlling link 76. The second controlling link 96 has its upper hooked end pivotally mounted on the seat 16 at the pivot 99 and supports the arm 70 which is connected thereto at pivot 72. The second controlling link 96 has a pivotal connection 98 at its lower end to the first controlling link 76 at a location spaced rearwardly relative to the pivotal and slidable connection between the first controlling link 76 and the arm 70. The spacing between the pivotal connection 99 of the second controlling link 96 on the seat and its pivotal connection 98 to the first controlling link 76 is greater than the spacing between the pivotal connection 72 of the arm 70 on the second controlling link 96 and the pivotal and slidable connection 80, 82 between the arm 70 and the first controlling link 76, the pin 80 being at the upper end of the slot 82 as shown in Fig. 1. Thus, in response to reclining movement of the back-rest, the second controlling link 96 will traverse a greater arc than that traversed by the arm 70 whereby the leg-rest 20 is translated both outwardly and upwardly in response to the drive imparted to the first controlling link via the guiding link 44 and the connecting link 48. The function of the second controlling link 96 is to guide the pin 80 in the slot 82 of the first controlling link 76 so that the pin 80 is urged downwardly toward the lower end of the slot (Fig. 2) in response to movement of the back-rest into the reclined position to provide an effectively longer support for the legs of the person using the chair.

The purpose of the present improved linkage arrangement may be more fully appreciated by considering typical but nonetheless illustrative dimensions of a chair. The average seat length is approximately 21" and the average leg-rest length is approximately 10". Thus the overall dimension for supporting the portion of the person's torso from the hip pivot to the feet is approximately 31". However, experience indicates that this dimension should be of the order of 38", and that a 40" support is optimum. By the linkage arrangement described whereby the leg-rest 20 is transmitted outwardly as well as forwardly relative to the seat, and with the slot 82 approximately 2" in length, it is possible to exceed the minimum permissible dimension and to arrive at optimum conditions. In this connection the overall height or width of the leg-rest cannot exceed 10" for the seat level should be at approximately 17"; and 7" are required for the depth of the seat and for clearance between the lower end of the leg-rest and the floor support.

In Figs. 4 and 5 there is illustrated a modification of the chair of Figs. 1 to 3 which is substantially identical to the embodiment illustrated in Figs. 1 to 3 inclusive. Accordingly, the corresponding parts have been desig-

nated by the same reference numerals as employed in Figs. 1 to 3 inclusive, but as part of a "100" series. In lieu of a support, seat and back-rest having a coaxial pivot or spaced apart pivots, in this embodiment the seat 116 and back-rest 118 are rigid with each other and together constitute the body supporting unit 114 which is pivoted on the support 112 at the pivot 138.

The leg-rest 120 is disposed adjacent to and beneath the forward end of the seat 116 and is supported thereon by identical linkage arrangements, arranged at each side of the chair. The linkage arrangements each embody an arm 170 pivoted on the second controlling link 196 and having a pin and slot connection 180, 182 to a first controlling link 176. The first controlling link 176 is pivotally connected at 186 to the leg-rest 120 and a connecting link 192 is pivotally connected between the lower end of the arm 170 and the leg-rest 120 at the respective pivots 190, 194. The second controlling link 196 is pivoted on the seat at the pivot 199 and has a pivotal connection 198 to the first controlling link 176 at a location spaced rearwardly of the pin and slot connection 180, 182. A guiding link 144 has its upper end pivotally mounted on the support 112 at the pivotal connection 160. The lower end of the guiding link 144 is pivotally connected at the pivotal connection 162 to the rearward end of the first controlling link 176.

In this embodiment, when the back-rest 118 is urged rearwardly to the reclined position, the unitary seat 116 is moved therewith and the leg-rest 120 is extended outwardly, upwardly and forwardly as seen in Fig. 5 by the linkage arrangement which is coordinated to the body-supporting unit 114.

From the foregoing illustrative embodiments of the invention, it will be appreciated that in accordance with the present invention an improved leg-rest control arrangement is provided which is compatible with the space and structural limitations imposed for chairs of this type, yet provide for the extension of the leg-rest in relation to the seat to comfortably accommodate the user in the reclined position. A latitude of modifications, change and substitution is intended in the foregoing disclosure and accordingly the appended claims should be construed broadly and in a manner consistent with the spirit and scope of the invention. In some instances, some features of the invention will be used without a corresponding use of other features.

What I claim is:

1. An improved leg-rest and control arrangement for use in a chair including a support member and a body-supporting member having a seat and a back-rest movably mounted on said support for rearward movement to various reclining positions, said arrangement comprising a leg-rest adapted to be moved to an elevated leg-supporting position as said body-supporting member moves rearwardly, an arm, a first controlling link, means providing a pivotal and slidable connection between said first controlling link and said arm, a second controlling link, means pivotally mounting said second controlling link on said seat at a first pivotal mount, means pivotally mounting said arm on said controlling link at a second pivotal mount spaced from said first pivotal mount of said second control link on said seat for turning movement relative to said second controlling link and said seat, said arm turning in a forwardly directed arc about said second pivotal mount as said body-supporting means and said second controlling link move rearwardly, means providing a pivotal connection between said second controlling link and said first controlling link, means pivotally connecting said first controlling link to said leg-rest, means operatively connecting said arm to said leg-rest, and means connecting said first controlling link to at least one of said members for coordinating the movement of said leg-rest to movement of said back-rest.

2. An improved leg-rest and control arrangement according to claim 1 wherein said last-named means

includes at least one guide link pivotally mounted on said support.

3. An improved leg-rest and control arrangement for use in a chair including a support member and a body-supporting member having a seat and a back-rest movably mounted on said support for rearward movement to various reclining positions; said arrangement comprising a leg-rest adapted to be moved to an elevated leg-supporting position as said body-supporting member moves rearwardly, an arm, a first controlling link, means providing a pivotal and slidable connection between said first controlling link and said arm, a second controlling link, means pivotally mounting said second controlling link on said seat at a first pivotal mount, means pivotally mounting said arm on said second controlling link at a second pivotal mount spaced from said first pivotal mount of said second control link on said seat for turning movement relative to said second controlling link and said seat, said arm turning in a forwardly directed arc about said second pivotal mount as said body-supporting means and said second controlling link move rearwardly, means providing a pivotal connection between said second controlling link and said first controlling link, means providing a pivotal connection between said first controlling link and said leg-rest, a connecting link pivotally connecting said arm

to said leg-rest, and means connecting said first controlling link to one of said members for coordinating the movement of said leg-rest to movement of said back-rest.

5 4. An improved leg-rest and control arrangement according to claim 3 wherein said body-supporting member includes a seat and back-rest mounted on said support for inclining and reclining movement respectively and wherein said last-named means includes a connecting link pivotally connected to said first controlling link and to said back-rest.

10 5. An improved leg-rest and control arrangement according to claim 3 wherein said body-supporting member includes a rigid seat and back-rest and wherein said last-named means includes a guiding link pivotally mounted on said support member and pivotally connected to said first controlling link.
